UNITED STATES PATENT OFFICE

168,036

RAILWAY VEHICLE

Basil E. Jones, Flossmoor, and Clarence V. Norby,
Chicago, Ill., assignors to Pullman-Standard
Car Manufacturing Company, Chicago, Ill., a
corporation of Delaware

Application January 23, 1952, Serial No. 18,182

Term of patent 14 years

(Cl. D66—1)

To all whom it may concern:

Be it known that we, Basil E. Jones and Clarence V. Norby, citizens of the United States of America, and residents, respectively, of Flossmoor, county of Cook and State of Illinois, and Chicago, county of Cook and State of Illinois, have invented a new, original, and ornamental Design for a Railway Vehicle, of which the following is a specification, reference being had to the accompanying drawings, forming part thereof.

In the drawings:

Fig. 1 is a perspective view of a railway vehicle showing our new design;

Fig. 2 is an end elevational view thereof; and

Figs. 3 and 4 are fragmentary side elevational views of the same.

The dominant features of our design reside in those portions shown by means of full lines.

We claim:

The ornamental design for a railway vehicle, substantially as shown and described.

BASIL E. JONES.
CLARENCE V. NORBY.
